UTILITY TABLE FOR SEWING

Anthony D. Glover, Austin, Tex.

Application June 24, 1954, Serial No. 31,141

Term of patent 14 years

(Cl. D33—14)

Des. 176,848

PAGE 2

Z. GUT

Fig. 3.

Fig. 1 is a perspective view illustrating one side and one end of a utility table for sewing embodying my new design, the other side and opposite end being the same in appearance as the side and end shown;

Fig. 2 is a side elevational view thereof; and

Fig. 3 is a view similar to Fig. 1 illustrating the table in open position.

I claim:

The ornamental design for a utility table for sewing, substantially as shown.
